(57) **CLAIM**

The ornamental design for the framed box card package, as shown and described.

DESCRIPTION

FIG. 1 is a perspective view of the framed box card package.

FIG. 2 is a front elevation view thereof;

FIG. 3 is a back elevation view thereof;

FIG. 4 is a right side elevation view thereof;

FIG. 5 is a left side elevation view thereof;

FIG. 6 is a bottom end plan view, which is a mirror image of the top end plan view thereof; and,

FIG. 7 is an alternate perspective view showing the top plane of FIG. 1 in an open position.

The portions shown in broken line are included for the purpose of illustration only and form no part of the claimed design.
